BOTTLE OR THE LIKE

Paul A. Marchant, Kansas City, Mo., assignor to Rexall Drug and Chemical Company, Los Angeles, Calif., a corporation of Delaware

Filed Dec. 29, 1966, Ser. No. 5,226

Term of patent 14 years

(Cl. D9—149)

FIG. 1 is a top plan view of a bottle or the like showing my new design;

FIG. 2 is an elevational view;

FIG. 3 is another elevational view taken from the right of FIG. 2; and

FIG. 4 is a fragmentary sectional view thereof taken on the line 4—4 of FIG. 1.

The dominant features of my design reside in the portions shown in full lines.

I claim:

The ornamental design for a bottle or the like, as shown and described.
